UNITED STATES PATENT OFFICE.

GEORGE O. KOLB, OF WEST HARTFORD, CONNECTICUT, ASSIGNOR TO GENERAL BAKING COMPANY, OF NEW YORK, N. Y., A CORPORATION OF NEW YORK.

DESIGN FOR WRAPPING PAPER.

Application filed January 16, 1922. Serial No. 227. Term of patent 3½ years.

To all whom it may concern:

Be it known that I, GEORGE O. KOLB, a citizen of the United States, and a resident of West Hartford, in the county of Hartford and State of Connecticut, have invented a new, original, and ornamental Design for Wrapping Paper, of which the following is a specification, reference being had to the accompanying drawings, forming part thereof, in which—

The figure is a view of a fragment of wrapping paper showing my new design.

I claim:

The ornamental design for wrapping paper shown in the accompanying drawing.

GEORGE O. KOLB.
